Primary Examiner — Karen S Acker(74) *Attorney, Agent, or Firm* — Dobrusin & Thennisch PC(57) **CLAIM**

The ornamental design for a foldable packaging, as shown and described.

DESCRIPTION

FIG. 1 is a perspective view of one embodiment of the present invention.

FIG. 2 is a side elevational view of the embodiment shown in FIG. 1, which is a mirror image of the other side.

FIG. 3 is a front elevational view of the embodiment shown in FIG. 1 which is a mirror image of the back.

FIG. 4 is a top elevational view of the embodiment shown in FIG. 1; and,

FIG. 5 is a bottom elevational view of the embodiment shown in FIG. 1.

The broken lines showing environment in the drawings are for illustrative purposes only and form no part of the claimed design.
